SHUTTLE FRICTION PAD AND ASSEMBLY

James E. Segee, Lawrence, and Wilfrid J. Gosselin, Methuen, Mass., assignors to U. S. Bobbin & Shuttle Co., Providence, R. I., a corporation of Rhode Island

Application December 17, 1948, Serial No. 65,766.

4 Claims. (Cl. 139—217)

1

This invention relates to what are known as friction pads such as are used in shuttles for looms, particularly those in which there is a shuttle block with a threading slot extending down from the top to produce an uniform friction or tension on the filling as the shuttle is picked back and forth at a very high speed. Such friction pads are shown in patents to Park, No. 2,087,607; Nova, No. 2,027,752; Tebo, No. 2,107,917; Tebo, No. 2,152,223; and Tebo, No. 2,170,541.

Near the back of the threading slot, there are two opposed metal pads into which the filling yarn slips, and then passes at every pick of the loom. Each pad has a nearly flat face along what we will call the friction or thread side and at the top there are wings each of which at the end of a curved edge extend out and back towards and forming part of a holding side. Near the bottom of each pad is a pinhole through which a pin passes, the hole being somewhat larger than the pin to allow each pad to move a short distance transversely of the axis of the shuttle.

At the top, each pad is bent in a curve outward or towards and beyond the holding side in the form of a neck, and from this neck, as now made, there are depending ears of U-shape each to enter a round hole or bushing in the shuttle block. Such pads are generally made of relatively thin metal bent into the desired shape, the thread side of each pad engaging filling thread when it is there and at other times engaging the filling side of the other pad.

It is highly desirable that each pad should be freely but not loosely movable transversely and its construction and supports should not permit one or both to bind at their top or bottom.

It has been customary to make the ears of U-shape, but, as the bushing or hole which each enters is round, they have a tendency to bind and the pin hole has been so punched that both its edges are right angles, thus leaving a sharp edge at the inside and also at the outside rims some times with a burr. This construction has a tendency to cause the pad to bind on its bottom as well as its top bearing.

Our construction prevents binding, and cutting of the filling thread but permits the thread to enter between the pads and to allow the force of the spring to produce the same pressure at all times on the thread whether it is running from the top of the thick part of the yarn package on the bobbin, from the middle, or from the bottom.

As the filling thread travels through between the pads at a very high speed and as occasionally a thin or thick spot appears in the thread, it is

2

very necessary that there should be a yielding of the pads transversely. To accomplish a resilient action there is usually a spring behind one or both pads so that when a thin spot passes, the friction will not be too much reduced or when a thick spot passes, there will be a yielding. The purpose is to produce as nearly as possible an uniform friction on the yarn, and to prevent it from unwinding from the bobbin too rapidly at one time, whereby it may form a loop which may catch on the nose of the shuttle block, and from passing too rapidly and too easily out of the shuttle eye, thus making a weak spot or a soft spot in the cloth.

15 On the other hand, if the thread is held back too much, when a thick spot passes between the pads, or if the friction and tension on the filling thread is too heavy, this may cause a break which is also highly objectionable.

20 Our invention consists of an improvement in each pad whereby the ears at the top forming a supporting head which engages the top bearing or bushing instead of being U-shaped are curved in a circle towards each other in almost an O shape and of forming the pin hole at the bottom as a tube with a rounded edge on the thread side whereby the yarn cannot catch on any part of it, the tube projecting on the holding side below the head and presenting a tubular contact 30 with the holding pin.

The bearings at top and bottom are cylindrical each presenting concentric concave to convex faces, all edges where binding might occur being rounded and, when installed, with a compression spring between them.

35 In the drawings Fig. 1 is a sectional elevational view on a vertical plane extending longitudinally through a shuttle block and with the different positions of the thread when passing through the friction pad as indicated.

Fig. 2 is a rear elevational view of a shuttle block with two friction pads in place.

Fig. 3 is an elevational view, very much enlarged, showing a single friction pad of our construction with parts of the top bushing bearing and the bottom pin bearing in position.

40 Fig. 4 is an elevational view as from the right of Fig. 3, but on a smaller scale with part of the shuttle block, pushing, and bearing head as well as the bearing pin all indicated.

45 Fig. 5 is an elevational view as from the back of Fig. 4, but omitting the threading block and pin.

50 Fig. 6 is a sectional elevational view as on a vertical plane which extends transversely through

a block with two friction plates but a single spring.

Fig. 7 is an isometric view as from the friction side of a friction plate, very much enlarged.

In the drawings S represents a shuttle of a well known type in which there is a threading block L which is usually of metal and in which is a longitudinal threading slot 29 which extends down from the top lengthwise of the shuttle axis. There are near the back of block L, one on each side of slot 29, oppositely disposed pads F, F, each of which has at the top a neck 30 and a head 31 which head extends into a cylindrical head bearing hole 33 in a bushing 34 fixed in a round head hole 37 in one side near the top of the slot 29. Each of these pads F has a holding pin hole 22 near its bottom through which a holding pin P passes in a well known manner.

When there is no thread in the shuttle, the high, narrow friction faces 20 engage each other from near the top to near the bottom. We will call this side the friction side and the other side 21 the holding side.

Wings 23, 23 are bent back between the top and bottom each from an edge 24 of the face 20 towards the holding side. As shown in Fig. 2, behind each pad F is a compression spring N which is usually held in place as by a screw 35 which can be turned to increase or decrease the tension of the spring N on a pad F.

The ears 32, 32 do not extend downward from a curved neck 30 in U-shape but curve down and around so that their free ends 36 almost touch to form an O. The head 31 and ears therefore have nothing to catch or bind, but can move freely in the top bearing hole 33.

If the springs N, N, or, if a single spring is used, the spring N is positioned approximately midway between such a head 31 and the pin hole 22 through which a pin P fits with an easy sliding fit each pad F can slide towards and away from the other or can rock enough to accommodate itself to any inequalities of filling thread and any position near the top, middle or bottom through which the thread passes.

To prevent the threat from catching between the pin hole 22 and pin P, or being pinched as each pad F rocks, we round the inner or friction side edge 26 of each hole 22 on the friction side 20 and this forms the base of a rim 25. This forms a rounded edge tubular pin hole.

The hole 22 is not punched but it and rim 25 are formed by a special tool and by an extruding process so that this tubular pin hole, on its outer or holding side edge 27 does not have a sharp cutting edge, as it does when a pin hole is punched, but is dull as shown in Fig. 3. However even if rim edge 27 is sharp, the rounded inner edge 26 prevents binding and permits a certain amount of rocking without wearing the pin P and even when the thread is threading or running from the bottom of a cone of thread near the bobbin tip as shown by the bottom, dotted lines T2 in Fig. 1, the wear is much less than in the usual construction. When the thread runs anywhere between T1 and T2, the pads F, F move easily with or against a spring N with no binding and little wear as each pad F has a tubular inside bearing member 31 at the top and at the bottom a tubular outside bearing member 25 which are parallel and each of which fits its holding means, hole 33 and pin P, with a smooth running fit.

In a common or standard size of shuttle, the

diameter of the inside of hole 22 should be about .01 of an inch greater than that of pin P, and the outside diameter of head 31 is from .01 to .03 less than the diameter of head bearing hole 33.

5 We claim:

1. The combination in a shuttle provided with a threading block with a threading slot extending down from the top, having on one side near the top of a cylindrical head bearing hole and 10 near the bottom, a holding pin; of a metal friction pad of thin metal which has a high, narrow substantially flat face on the friction side, wings between the top and bottom which extend back each from an edge of the flat face towards a holding side, a neck at the top which curves back at the holding side carrying integral downwardly extending ears which are curved toward each other to form a substantially tubular bearing head, and a tubular pin hole near the bottom of each pad with a rounded edge on the friction side and a rim projecting on the holding side parallel with the head, the edge of the projecting rim on the holding side being dull, so as to form a rounded edge tubular holding pin hole; with a compression spring positioned between the tubular bearing head and the tubular holding pin hole.

2. A metal friction pad for loom shuttles of thin metal which has a high, narrow substantially flat face on the friction side, wings between the top and bottom which extend back each from an edge of the flat face towards a holding side, a neck at the top which curves back at the holding side carrying integral downwardly extending ears which are curved toward each other to form a substantially tubular bearing head and a tubular pin hole near the bottom of each pad with a rounded edge on the friction side and a rim projecting on the holding side parallel with the head, the edge of the projecting rim on the holding side also being dull so as to form a rounded edge tubular pin hole.

3. A metal friction pad for loom shuttles of thin metal which has a high, narrow substantially flat face on the friction side, wings between the top and bottom which extend back each from an edge of the flat face towards a holding side, a neck at the top which curves back at the holding side carrying integral downwardly extending ears which are curved toward each other to form a substantially tubular bearing head and a tubular pin hole near the bottom of each pad with a rounded edge on the friction side and a rim projecting on the holding side parallel with the head, so as to form a rounded edge tubular pin hole.

4. A metal friction pad for loom shuttles of thin metal which has a high, narrow, flat face on the friction side, wings between the top and bottom which extend back each from an edge of the flat face towards a holding side, a neck at the top which extends back at the holding side carrying integral downwardly extending ears which are curved toward each other to form a substantially tubular bearing head and a tubular pin hole near the bottom of each pad with a rounded edge on the friction side and a rim projecting on the holding side parallel with the head, so as to form a rounded edge tubular pin hole.
